PORTABLE PROJECTION SCREEN SUPPORTED ON AN EXTENSIBLE POLE

Frank D. Sayer and Gilford D. Hudson, Warsaw, Ind.,
assignors to Da-Lite Screen Company, Inc., Warsaw,
Ind., a corporation of Illinois

Filed Feb. 28, 1961, Ser. No. 64,097

Term of patent 14 years

(Cl. D61—1)

FIG. 1

FIG. 2

FIG. 3

FIGURE 1 is a front elevation view of a portable projection screen supported on an extensible pole showing our new design.

FIG. 2 is a side elevation of FIG. 1 showing the pole in extended position and the portable screen in closed position.

FIG. 3 is a rear elevational view of FIG. 1 showing the projection picture in open position.

We claim:

The ornamental design for a portable projection screen supported on an extensible pole, as shown.
